Fig. 2

Fig. 3

Fig.4

FIGURE 1 is a front top and left side perspective view of a data matrix decoder showing my new design;

FIGURE 2 is a front, top and right side perspective view;

FIGURE 3 is a back, bottom and right side view, and

FIGURE 4 is a left side elevational view, the right side being substantially a mirror image thereof. Portions of the figures are shaded to indicate color contrast and certain of the push buttons are shown in depressed position in FIGURE 1 for illustrative purposes only.

I claim:

The ornamental design for a data matrix decoder, as shown and described.
